Harry Gruftchley.

By his Attorney *Ab Dickson*

UNITED STATES PATENT OFFICE.

HARRY CRUTCHLEY, OF JERSEY CITY, NEW JERSEY, ASSIGNOR TO UNDERWOOD TYPEWRITER COMPANY, OF NEW YORK, N. Y., A CORPORATION OF NEW JERSEY.

TYPE-WRITING MACHINE.

942,776.

Specification of Letters Patent. Patented Dec. 7, 1909.

Application filed November 25, 1908. Serial No. 464,652.

To all whom it may concern:

Be it known that I, HARRY CRUTCHLEY, a citizen of the United States, residing in Jersey City, in the county of Hudson and 5 State of New Jersey, have invented certain new and useful Improvements in Type-Writing Machines, of which the following is a specification.

This invention relates to the mechanism 10 for vibrating the ribbon to cover and uncover the printing point at each type stroke.

The principal object of the invention is to provide simple and effective means which 15 may be readily applied to existing type-writing machines, for causing the ribbon at will to remain stationary below the printing point at the type strokes, to enable stencils to be written.

In carrying out the invention, I employ a 20 rocker-arm, which is operated by another arm that vibrates at the key strokes in the well known Underwood machine, to which my invention is shown as applied. The rocker-arm has a pin-and-slot connection 25 with a ribbon-vibrating lever. Said rocker-arm is disconnectable from said vibrating arm at the will of the operator, so that the ribbon will remain below the printing point at the type strokes. This disconnection is 30 effected by the expedient of providing said rocker-arm with an axially movable wrist. Normally the wrist lies in a slot in said constantly vibrating arm, but by turning a finger-piece the operator can withdraw said 35 wrist, so that vibrations are no longer communicated thereby to said rocker arm, and hence the ribbon is not vibrated.

Other features and advantages will hereinafter appear.

40 In the accompanying drawings, Figure 1 is a front perspective view of the universal bar mechanism and ribbon-vibrator of an Underwood front strike writing machine, showing my improvements applied thereto; the parts being shown in normal positions, and the ribbon connected up to vibrate at 45 each type stroke. Fig. 2 is a view of said parts seen at Fig. 1, but showing the ribbon disconnected, so that it will not vibrate at the type strokes. Fig. 3 is a sectional end 50 elevation, showing the parts in normal positions. Fig. 4 is a view similar to Fig. 3, but showing the ribbon carrier vibrated up to cause the ribbon to cover the printing 55 point at the type stroke. Fig. 5 is a view

similar to Fig. 3, but showing the ribbon disconnected, and the constantly vibrating arm as having been elevated without affecting the ribbon.

Type-bars 1 strike through a ribbon 2 on 60 the front side of a platen 3. Heels 4 on the type-bars press rearwardly a curved universal bar 5, which is fixed upon a frame 6 carried upon a rocking frame 7, which includes a shaft 8. Fixed upon said shaft is a downwardly and forwardly inclined arm 9 having a longitudinal slot 10; said arm 9 vibrating up and down at the type strokes.

In engagement with the slot 10 is a wrist 11, which projects through a bearing 12 in 70 a rocker arm 13, the latter mounted upon a shaft 14 extending across the machine and supported in bearings 15. It will be understood that vibrations of the arm 9 are communicated to the arm 13. Upon the latter 75 is fixed an upright extension 16 having at its upper end a vertical slot 17 to engage a pin 18 provided upon an arm 19 of a bell-crank lever 20, to which is attached a vertical sliding member 21 carrying the ribbon 80 2. As the rocker arm 13, 16 swings forwardly and backwardly, the ribbon lever 20 is swung up and down, so that the ribbon is carried up to cover the printing point when the type strikes, and is then dropped to dis- 85 close the writing.

The wrist 11 is adapted to be withdrawn from the slot 10, being for this purpose mounted for axial movement through the bearing 12 in the rocker-arm 13. The wrist 90 itself is fixed to a carrier 22, which is in the form of an arm similar to 13 and having a boss or head 23 in which said wrist is fixed. This carrier 22 is mounted to turn upon the shaft 14 to accommodate the rocking of the 95 arm 13; and it is also movable along said shaft to withdraw the wrist 11 from the slot 10. For this purpose, the carrier 22 is fixed upon a long hub or tubular shaft 24, which 100 can slide along the shaft or rod 14. Such sliding movement is effected by a shifter arm 25 fixed upon and depending from the rock shaft 26 and having at its lower end a pin 27 to work between forks 28 projecting up from the hollow shaft 24; this connection 105 being sufficiently loose to permit the shaft 24 to rock at the type strokes, and also to permit the shifter arm 25 to slide said shaft 24 to and fro along the rod 14. Said rock shaft 26 extends horizontally forward 110

through the front vertical plate or wall 29 of the machine, where it is provided with an upstanding arm 30 having a finger-piece 31. Upon the top of the arm 30 is formed 5 an index 32, and a plate 33 is fixed to the front wall 29 and provided with marks designated as "S" and "R".

When it is desired to stop the ribbon from vibrating during the type strokes, the finger-piece 31 is pressed to the left from the Fig. 10 position, so that the index 32 will register with the letter "S", which stands for "stencil." Such movement shifts the arm 25 to the right, and thereby slides the wrist 15 carrier 24, 22 in the same direction, and withdraws the wrist 11 from the slide 10, as at Fig. 2. When it is desired to restore the activity of the ribbon, the finger-piece 31 is pressed toward the right, so that the index 20 32 registers with the letter "R", meaning "ribbon", when the parts are turned to the Fig. 1 position. A detent-spring 34 engages notches 35, 36 in a collar 37 fixed upon the rock-shaft 26, so as to hold the parts in either Fig. 1 or Fig. 2 position.

The platen 3 is carried upon a frame having a roll 38 to run upon a rail 39, which can be shifted up and down, to cause different types to print; and the ribbon lever 20 is 30 pivoted upon a bracket 40 fixed to said rail; the slot 17 accommodating the up and down shift movements of the rail and the lever arm 19.

Variations may be resorted to within the 35 scope of the invention.

Having thus described my invention, I claim:

1. In a typewriting machine, the combination of a ribbon-vibrating lever, a rocker 40 arm engaging said lever and mounted on a shaft, a wrist engaged by said rocker arm, a member reciprocating at the type strokes and normally engaged by said wrist, a wrist-carrier mounted upon said shaft to rock with 45 said arm, said carrier movable along said shaft to withdraw said wrist from said reciprocating member, and means to adjust said carrier.

2. In a typewriting machine, the combination of a ribbon-vibrating lever, a rocker 50 arm engaging said lever and mounted on a shaft, a wrist engaged by said rocker arm, a member reciprocating at the type strokes and normally engaged by said wrist, a wrist-carrier mounted upon said shaft to rock with 55 said arm, said carrier movable along said shaft to withdraw said wrist from said reciprocating member, means to adjust said carrier, and a detent to hold said carrier at 60 different adjustments.

3. In a typewriting machine, the combination with a platen-shift rail, of a ribbon-vibrating lever mounted thereon and having a depending arm provided with a pin, a 65 rocker-arm mounted at its lower end upon a

shaft and at its upper end having a vertical slot to engage said pin and permit up and down shifting of the platen-shift rail, a wrist movable axially in said rocker arm, a slotted vibrating arm fixed upon a rocking 70 support of a universal-bar frame which reciprocates at the type strokes, a sleeve upon said shaft, said sleeve having an arm in which said wrist is fixed, a forwardly extending shaft, an arm upon the latter and 75 having an engagement with said sleeve, a finger-piece and index upon said forwardly extending shaft, and a detent connected to the latter shaft for holding said wrist either in or out of engagement with said slotted 80 arm.

4. In a typewriting machine, the combination with a vibrating lever 9, of a ribbon-vibrating rocker arm, a wrist 11 movable axially in said rocker arm to connect and 85 disconnect it from said lever, a carrier upon which said wrist is mounted, said carrier mounted to vibrate idly with said rocker arm and also to withdraw and return said wrist from engagement with said lever 9, 90 and a manually controlled member mounted upon the framework and loosely connected to said carrier to shift said wrist.

5. In a typewriting machine, the combination with type keys and a universal-bar 95 frame operated thereby, of a ribbon vibrator, a lever connected to the ribbon vibrator having a downwardly extending arm, an upwardly extending rocker arm fixed at its lower end upon a shaft extending across 100 and fixed in the machine frame, said rocker arm provided with an upwardly extending auxiliary arm provided at its upper end with a slot engaged by a pin carried by the downwardly extending arm of the lever, a 105 second rocker arm extending parallel with the first rocker arm and secured at its lower end upon a hollow shaft mounted upon the first shaft for endwise sliding movement, a wrist carried at the upper end of said second 110 rocker arm, said wrist engaging a bearing in the upper end of the first rocker arm for axial movement, and a downwardly and forwardly extending vibrating arm fixed upon the universal-bar frame, said arm provided 115 with a slot at its lower end normally engaged by the wrist to operate the ribbon vibrator at the type strokes.

6. In a typewriting machine, the combination with type keys and a universal-bar 120 frame operated thereby, of a ribbon vibrator, a lever connected to the ribbon vibrator having a downwardly extending arm, an upwardly extending rocker arm fixed at its lower end upon a shaft extending across and 125 fixed in the machine frame, said rocker arm provided with an upwardly extending auxiliary arm provided at its upper end with a slot engaged by a pin carried by the downwardly extending arm of the lever, a second 130

rockers are extending parallel with the first rocker arm and secured at its lower end upon a hollow shaft mounted upon the first shaft for endwise sliding movement, a wrist 5 carried at the upper end of said second rocker arm, said wrist engaging a bearing in the upper end of the first rocker arm for axial movement, a downwardly and forwardly extending vibrating arm fixed upon 10 the universal-bar frame, said arm provided with a slot at its lower end normally engaged by the wrist to operate the ribbon vibrator to cover and uncover the printing point at the type strokes, and a forwardly 15 extending shaft having an arm to engage the hollow shaft, and provided with a finger piece to throw the wrist into and out of engagement with the slotted vibrating arm at will.

20 7. In a typewriting machine, the combination with type keys and a universal-bar frame operated thereby, of a ribbon vibrator,

a lever connected to the vibrator and having a downwardly-extending arm, a pair of parallel rocker arms, one arm secured at its lower end to a shaft and having a slot in its upper end engaged by a pin on the downwardly-extending arm of the ribbon-vibrator lever, and the other rocker arm mounted for axial movement on said shaft and provided 25 with a wrist to engage a bearing in the first rocker arm for axial movement; a reciprocating arm fixed upon the universal-bar frame to be reciprocated thereby at the type strokes, said reciprocating arm provided 30 with a slot normally engaged by the wrist, and a finger-piece connected to the wrist-carrying rocker-arm to throw said wrist into and out of engagement with the reciprocating arm at will.
